UNITED STATES PATENT OFFICE.

CHARLES SIDNEY SMITH, OF ST. JOHNSBURY, VERMONT.

TIRE-SETTER.

SPECIFICATION forming part of Letters Patent No. 637,834, dated November 28, 1899.

Application filed December 7, 1898. Serial No. 698,504. (No model.)

To all whom it may concern:

Be it known that I, CHARLES SIDNEY SMITH, a citizen of the United States, residing at St. Johnsbury, in the county of Caledonia and State of Vermont, have invented a new and useful Tire-Setting Machine, of which the following is a specification.

My invention relates to that class of tire-setting machines in which a series of radially-arranged compression-jaws are operated by fluid-pressure to compress or upset the tire or band upon a wheel or hub.

The object of the invention is to provide a machine of this character which will be simple in construction, effective and quick in operation, and frictionless to the highest degree. This object I attain by the mechanism shown in the accompanying drawings, in which—

Figure 1 is a transverse vertical section through my improved machine with a wheel in position. Fig. 2 is an enlarged detail view showing the ball-bearing connection between one of the compression-levers and the top of the operating-cylinder. Fig. 3 is a detail view of a modified connection between one of the compression-levers and one of the compression-bars; and Fig. 4 is a plan of the machine, a portion being broken away.

A is the base of the machine, provided with a circularly-arranged series of uprights or posts 5, securely held by inclined braces α α^2 , as shown in Fig. 1, and on the upper ends of these posts or uprights is secured a ring or annular top plate 2, provided at intervals in any suitable manner with fulcrum-bearings 2^a, over which hook the outwardly-projecting hooked upper ends 1^a of the upwardly-projecting members of the angle-levers 1, the horizontally-extending long arms of said levers extending radially inward and resting loosely upon the top of the operating-cylinder 9. This cylinder 9 moves vertically upon a stationary cylinder 10, secured upon the base A concentric with the ring 2. The space 11 between the cylinder ends is supplied with any suitable fluid under pressure by means of a pipe 12, which extends up through the stationary cylinder, as shown in Fig. 1.

The top of the cylinder 9 is provided with radial grooves 16, and the under faces of the levers 1 are provided with longitudinal grooves 15, registering with the grooves 16, and a ball

or roller 14 is placed in every pair of such registering grooves, as shown in Fig. 2, so that friction will be relieved at these points.

8 is a small ring concentric with the ring 2 and in a lower horizontal plane. This ring 8 is mounted on the upper ends of a circularly-arranged inner series of uprights or posts 8', suitably braced to the base, as at α^3 , and the upper face of this ring 8 is preferably inclined upwardly and inwardly from its outer edge, as shown in Fig. 1, and provided with radial grooves in such inclined face to receive the balls or rollers 7.

3 designates the radially-arranged horizontal series of compression-bars, having a knife-edge bearing 3^b at the outer sides of their outer shouldered ends 3^a with the adjacent inner edges of the vertical members of the compression-levers 1 and also connected to said levers by the pivoted links 4, as shown in Fig. 1, or by the socket-like connection 4^a. (Shown in Fig. 3.) The inner ends of the compression-bars 3 are beveled, as shown at 6, to correspond with the bevel of their supporting-ring 8, and their lower beveled ends are longitudinally grooved, as shown in dotted lines, Fig. 1, to receive balls or rollers 7. This beveling of ring 8 and bars 3 causes the latter to be maintained in a horizontal position as they are forced inwardly and upwardly by the levers 1, as shown in dotted lines, Fig. 1.

The wheel or other circular part 13 having a band or tire to be upset thereon is placed upon the upper sides of the compression-bars 3 and within the circle described by the series of shoulders 3^a and fluid under pressure is admitted to the space 11. The cylinder 9 will be forced upwardly, carrying with it the inner ends of levers 1, which slide inwardly on the top of the cylinder. The upward movement of the levers 1 causes their upwardly-projecting ends to move inwardly against the horizontally-sliding bars 3, which support the article operated upon, and the shouldered ends 3^a of these bars grasp the cold tire or band and compress it or upset it upon the rim of the wheel or other surface. As the bars 3 move inwardly their outer shouldered ends are also slightly raised and the inner inclined ends 6 will ride up the inclined face of ring 8 or inclined surfaces

formed thereon, and so the horizontal position of the bars will be maintained. When the cylinder 9 is relieved of pressure, the parts will resume their normal position, as shown 5 in full lines, Fig. 1.

I do not intend confining myself to the particular details shown, as various modifications may be made without departing from the scope of my invention.

10. What I claim is—

1. The combination with a circularly-arranged series of angle-levers fulcrumed at the upper outer portions of their upwardly-extending members upon a suitable support, 15 and having their horizontally-extending members extending radially inward, an operating mechanism engaging the converging inner ends of said levers, and horizontal compression-bars having shouldered outer ends to 20 receive a wheel or other body within them, and said outer ends bearing against the inner sides of the vertically-extending members of the levers below their fulcrums, and a support on which the compression-bars slide 25 at their inner converging ends.

2. The combination with a horizontal ring mounted on suitable supports and a series of angle-levers having outwardly-hooked upper ends or fulcrums, engaging bearings on said 30 ring, and having their long arms extending radially inward, an operating mechanism engaging the converging inner ends of said levers, of a series of horizontal compression-bars having shouldered outer ends engaging 35 the inner edges of said levers below said hooks or fulcrums and supported from said levers, an inner lower concentric ring on which the converging inner ends of the bars rest and slide; substantially as described.

40. 3. The combination with a horizontal ring, the series of angle-levers having outwardly-projecting fulcrum-hooks at the upper ends of their vertically-extending arms fulcrumed on the ring; the horizontal long arms of the lever 45 extending inwardly and provided with an operating mechanism, of a series of radial compression-bars operatively engaged at their outer shouldered ends by the inner edges of the said vertically-extending arms, and an 50 inner lower horizontal ring supporting the inner converging ends of the bars; the adjacent surfaces of the bars and inner ring being beveled to cause the bars to maintain their horizontal position; substantially as de- 55 scribed.

4. The combination with the horizontal ring,

the angle-levers fulcrumed at the upper ends of their vertically-extending arms on bearings at the inner periphery of the ring, and having their longer arms extending horizontally 60 inward, and a vertically-movable cylinder on which the inner converging ends of said arms rest, of a horizontal series of radial compression-bars engaged at their outer shouldered ends by the inner edges of said angle-levers 65 below the fulcrums thereof, and an inner lower horizontal ring on which the inner converging ends of said bars rest and slide.

5. The combination with the horizontal ring and the angle-levers fulcrumed thereon with 70 their horizontally-extending long arms extending inwardly, and an operating mechanism engaging said ends, of a series of horizontal compression-arms having a knife-edge bearing at their outer shouldered ends with 75 the inner vertically-extending edges of the short arms of said levers, and an inner lower horizontal ring on which the inner converging ends of the bars rest and slide inwardly and 80 upwardly.

6. The combination with the horizontal ring and the angle-levers fulcrumed thereon with their lower long arms extending horizontally inward and an operating mechanism engaging the inner converging ends of said levers, of a 85 series of horizontal compression-bars having a socketed and knife-edge connection at their outer ends with the inner edges of the vertically-extending short arms of said angle-levers as shown at 4^a, and an inner lower horizontal 90 ring on which the inner converging ends of the bars rest and slide.

7. The combination with the outer upper horizontal ring, the angle-levers fulcrumed thereon at their upper ends, and having their 95 longer arms extending horizontally inward, an operating cylinder over which the converging ends of the levers project and balls or rollers interposed between said lever ends and cylinder, of the horizontal compression-arms engaged at their outer ends by the inner 100 edges of the vertically-extending arms of said levers below their fulcrums, and an inner lower horizontal ring supporting the inner converging ends of the compression-bars; the 105 adjacent surfaces of the rings and bars being correspondingly inclined and separated by balls or rollers.

CHARLES SIDNEY SMITH.
